UNITED STATES PATENT OFFICE.

GEORGE W. MULLER, OF WASHINGTON, DISTRICT OF COLUMBIA.

RAILWAY-BED STRUCTURE.

Application filed July 9, 1925. Serial No. 42,541.

To all whom it may concern:

Be it known that I, GEORGE W. MULLER, citizen of the United States, residing at Washington, District of Columbia, have invented certain new and useful Improvements in Railway-Bed Structures, of which the following is a specification.

This invention relates to the construction of the road bed and tracks of railways, and has for one of its objects to improve the construction and increase the load resisting qualities of the rails and the supporting bed or foundation, to withstand the material increase of the weight of the present rolling stock.

Another object of the invention is to provide a railway track structure formed of a plurality of superimposed members disposed in longitudinal alignment with the joints between the members breaking, or in staggered relation.

Another object of the invention is to provide a railway track structure formed of a plurality of superimposed members in longitudinal alignment with the joints between the members breaking or in staggered relation and with cross ties between certain of the members.

Another object of the invention is to provide a railway tie of improved construction and increased weight, strength and pressure resisting qualities.

With these and other objects in view the invention consists in certain novel features of construction as hereinafter shown and described and then specifically pointed out in the claims, and in the drawings illustrative of the preferred embodiment of the invention:

Figure 1 is a side elevation of portions of the abutting ends of a pair of the rails including the joint by which they are connected, and end views of a plurality of the improved ties.

Figure 2 is a plan view of the parts shown in Figure 1.

Figure 3 is a side elevation of one of the improved ties and the top or running rail and the under rail or support, the rails being in transverse section.

Figure 4 is a plan view of the parts shown in Figure 3.

Figure 5 is a side elevation enlarged, of sections of one of the improved upper or running rails and one of the lower or sup-

porting rails with one of the improved ties in transverse section on the line 5-5 of Figure 2, looking in the direction of the arrow.

Figure 6 is a side elevation of the parts shown in Figure 5, with the rails in transverse section on the line 6-6 of Figure 5.

Figure 7 is a plan view, on a reduced scale, of a section of a railway track, illustrating the construction and the manner of arranging and coupling the terminals of the members.

Figure 8 is a side view of the structure shown in Figure 7.

Figure 9 is a detail, enlarged, illustrating a modification in the construction.

The very material increase in the size and weight of locomotives, cars and other rolling stock of railways at the present time necessitates the corresponding increase in weight, strength, and resisting power of the rails, ties and foundation or bed portions, to enable them to withstand the increased strain and pounding action of the relatively heavy trains, especially when running at high speed, and the principal object of the present invention is to provide a construction of increased strength and resisting power which will effectually support the rolling stock and prevent deflection of the rails and ties, and the resultant uneven motion of the vehicles passing over the rails.

The improved tie is formed with a body of concrete or other plastic material and is represented as a whole at 10, with a base portion laterally extended as shown at 11 and with drainage gutters 12 intermediate the sides and sloping from the center toward the ends, as shown in Figure 3.

Embedded within the concrete body are a plurality of slightly yieldable members 13 of wood or the like, and a plurality of reinforcing elements indicated at 14.

The members 14 may be of any required form, for instance, sheets of metal with a plurality of clefts cut therethrough in staggered relation and the cleft metal drawn apart to separate the bands between the clefts in a well known manner.

The webs thus cleft and separated being embedded in the plastic material as the tie is molded, materially increase the strength of the completed tie.

Disposed upon each of the ties at the point where the main or upper load bear-

ing rails are to pass is a bearing block of wood, or like material, to relieve the shock, which is designated by the numerals 15.

The improved rail is formed of a lower or base portion including a tie flange 16 and web portions 17, the latter having its upper terminal 18 formed with inclined sides.

The wearing portion of the rail comprises 10 a head 19 and web 20, the head portion having a longitudinal channel 21 to receive the tapered head 18 of the web 17, as shown.

In the form of the rail illustrated in Figures 3, 4, 5 and 6, head portions 19 are shown 15 at each side of the web 17, and each with a longitudinal channel 21, one head portion bearing upon the upper face of the tie flange 16, as shown in Figures 3 and 6. The rail portion thus constructed may be reversed to 20 bring either head portion uppermost, and thus present either head for engagement by the rolling stock.

The construction of the rail is the subject-matter of a separate application, and 25 needs no further description.

Bearing beneath the tie structures and in longitudinal alignment with the bearing rail is a support 22, which may be old worn out rails of the ordinary construction, as 30 shown.

The flange portions 16 of the upper rails are secured in position upon the blocks 15 by clamp members 23, while the lower supports 22 are held in position upon the lower 35 face of the tie by like clamp plates 24, the two sets of plates being coupled through the body of the tie by a novel arrangement of clamping devices as illustrated in Figure 5.

Embedded in the body of the tie in alignment 40 with the clasp members 23 and 24 are sleeve devices 25, each sleeve being enlarged at the upper end as represented at 26 to hold them from movement downwardly through the tie.

45 Each sleeve is internally threaded with right and left hand threads, as represented in Figure 5, and engaging the right hand thread is a clamp bolt 27 provided with a wrench receiving head 28, each bearing on one of the clamp plates 23, while a like clamp bolt 29 is left hand threaded to engage the left hand thread of each sleeve and each with a wrench receiving head 30 bearing upon one of the clamp plates 24.

55 When the ties are disposed in position the clamp members 24 and the clamp bolts 29 are applied, to rigidly couple the lower rails 22 to the lower wider faces of the ties, and the lower rails embedded in the ballast, indicated at 31. By this means the ties are firmly anchored to the lower rails and the latter firmly anchored in turn in the ballast or other foundation.

60 The bearing blocks 15 are then disposed in 65 position and the base portion 16 of the upper

70 rail device disposed on the blocks and the clamp plates 23 and bolts 27 applied to firmly couple the base of the upper rail in position. Then the rotation of the bolts 27 by a wrench or the like applied to the heads 28 will result in a binding force to firmly clamp the parts together.

75 By this arrangement the lower rails 22 are firmly coupled to the ties from beneath and the upper rail devices firmly coupled to the ties from above, and independently of the lower rail.

80 The lateral enlargements 26 of the sleeves operate as stops to prevent the sleeves being pulled out of the ties when strain is applied by the bolts 30, while at the same time, the latter coating with the clamps 24 and lower rails 22 prevent the sleeves from being drawn upwardly by strain applied to the bolts 27.

85 After the base portions 16 and 17 of the upper rail structures are in position as above described, the load bearing rails 19 will be applied and the clamp plates 32 attached by the clamp bolts 33.

90 Interposed between the lower wider face of the tie 10 and the supports 22 is a plate 26, preferably of one fourth inch steel plate, indicated at 34, to provide a supporting yieldable or wear member to receive the jars 95 or concussions between the rail and tie and absorb them and prevent them from being communicated to the material of the tie.

95 At their meeting ends the upper or bearing rails 19 will be reversely beveled as 100 shown at 35 in Figure 2, and certain of the clamp bolts 33 will be passed through the beveled or scarf'd portions 35, as shown.

105 The wide spread of the base of the improved tie is an important feature as the ground footing or spread of the tie insures the safe carrying of a corresponding increase in the weight of the rolling stock, practically four fold.

110 The wood members 13 in the tie are also 110 an important feature, as they operate to deaden the sound and absorb the noise. In addition to this the wood members decrease the weight of the tie without decreasing the pressure resisting qualities, but on the contrary increase the strength of the tie.

115 The wood members may be of any suitable shape or size, and portions of small trees or straight branches may be employed where available.

120 The improved tie is supported by the usual rock ballast, indicated conventionally at 36, and the lower supporting rails 22 will be embedded in the ballast.

125 The bearing members 15 may be partly embedded in the tie structure, as shown at 37 in Figures 1 and 3.

130 Under certain conditions it may be found advantageous to bridge the space between the ties by a metal plate 38 having down-

turned ends 39 to engage the rims of the gutters 12, and covering the plates with a layer of moisture proof material 40 to shed rain and snow, and draining it off and preventing it from settling between the ties.

It will be noted that the structure including the two part upper rail portion formed of superposed members 16, 17 and 19, with their terminals overlapping, the lower rail portions 22 and their confronting terminals overlapping both the terminals of the two part upper rail portion, the ties between the upper and lower rail portions, the couplings between the several rail portions, and the clamping means whereby the several rail portions and the ties are clamped together, constitutes a truss-like structure in which all the parts are firmly and mutually reinforced, and produce a structure capable of effectually withstanding the severe strains to which it will be subjected when in use.

The several rail sections are substantially of uniform length, generally about thirty feet, and the joints of the rail portions 19 will preferably be located about ten feet from one of the joints of the base rails 16 and 17, and twenty feet from the other joint, and the joints of the lower rail members located intermediate the joints of both members of the upper rail portions.

The scarfed joints 35 of one of the upper rails 18 overlap the scarfed joints of the other upper rail, as indicated in Figure 7, while the joints between the terminals of one of the rail portions 16 and 17 are located intermediate the joints of the rail portions 19, and the joints between the terminals of the lower rail portions 22 are located opposite the spaces between the joints of the other rail portion 19 and opposite the spaces between the joints of the rail portions 16 and 17.

By this means the joints are uniformly distributed throughout the whole length of both of the railway tracks, and the strains and resistance correspondingly uniformly distributed, and a very rigid and firm track-
age produced in which all the parts coact to effectually resist any tendency to settle or produce unevenness of surface, especially where relatively soft or yielding portions of the road bed are encountered.

The rigid formation of the improved track forms a bridge or truss-like construction which effectually prevents any uneven settling, as will be obvious.

A track construction as herein described materially reduces the tendency to washout in event of heavy rains or from melting snow, and also of abnormal rain fall or snow accumulations, resulting in washouts for short distances, and the rigid construction of the track will hold it up and prevent it from settling into the washout portions.

The structure herein defined is of the

laminated order which is the strongest and most rigid construction in use, as all the parts coact, as before stated, to mutually support and reinforce each other.

The rigid construction materially decreases the wear and tear of the locomotive and other rolling stock, and correspondingly reduces the cost for maintenance and repairs.

The rigid construction also very materially reduces the tendency of the locomotives and cars to run off or overturn, as the tracks are held to their true position and prevented from lateral or vertical movement.

By the foregoing it will be obvious that the structure herein disclosed is in the nature of a truss or bridging element in which all parts mutually support and reinforce each other, and in event of one or more portions being subjected to abnormal strains, the remaining portions automatically and successfully resist any tendency of the strained portion from being displaced, thus compensating for any strains that may be developed at any one point throughout the structure, but all parts will be rigidly held in their true and unchangeable relation.

What is claimed and desired to be secured by Letters-Patent is:—

1. A railway tie of plastic material, having upon its upper surface a rail cushion, the said tie having rail-securing means spaced apart and passing upwardly through the body of the tie, and sound deadening members located within the body of the tie, the said sound deadening members being surrounded on all sides by the said plastic material moisture tight, and the said sound deadening members comprising pieces of compressible and yielding material extending lengthwise with respect to the tie.

2. A railway tie of plastic material, having upon its upper surface a rail cushion, the said tie having rail-securing means spaced apart and passing upwardly through the body of the tie, and sound deadening members located within the body of the tie between the said spaced rail-securing means, the said sound deadening members being surrounded on all sides by the said plastic material moisture tight, and the said sound deadening members comprising pieces of compressible and yielding material extending lengthwise with respect to the tie.

3. A railway tie of plastic material, sleeve devices embedded in the tie with right and left hand threads, load bearing rails above the tie, protecting plates arranged upon the lower surface of the tie, supporting rails beneath the tie, the said supporting rails arranged below and against the said protecting plates, clamp bolts threaded to engage the upper threads of the sleeves and operating to bind the load bearing rails relative to the tie, and clamp bolts passing through

- the said plates and threaded to engage the other threads of the sleeves and operative to bind the supporting rail relative to the tie.
5. A railway tie of plastic material, sleeve devices embedded in the tie with right and left hand threads, means for holding said sleeves from displacement relative to the tie, load bearing rails above the tie supporting rails beneath the tie, clamp bolts threaded to engage one of the threads of the sleeves and operating to bind the load bearing rails relative to the tie, and clamp bolts threaded to engage the other threads of the sleeves and operative to bind the supporting rail relative to the tie.
6. A railway tie of plastic material, sleeve devices embedded in the tie and with right and left hand threads, bearing blocks on the tie, load bearing rails upon the blocks, supporting rails beneath the ties, upper clamp devices upon said blocks and extending over the load bearing rails, lower clamp devices beneath the ties and extending over the supporting rails, clamp bolts operating through the upper clamp devices and the bearing blocks and threaded to engage one of the threads of the sleeves, and clamp bolts operating through the lower clamp devices and threaded to engage the other threads of the sleeves.

6. A railway construction comprising tie members, upper rail portions of superposed members bearing upon the ties with their terminals overlapping, means for coupling the confronting ends of the upper rail portions, lower rail members beneath the ties with the terminals thereof overlapping the joints of both portions of the upper rail, means for coupling the confronting ends of the lower rail members, and means for clamping the several rail portions and ties together.

7. A railway tie of plastic material, sleeve devices embedded in the tie with securing means, load bearing rails above the tie, supporting rails beneath the tie, and clamping means coacting with the sleeve securing means and operating to bind the load bearing rails and the supporting rails relative to the tie.

8. A railway tie of plastic material, sleeve devices embedded in the tie with securing means, load bearing rails above the tie, supporting rails beneath the tie, clamping means coacting with the sleeve securing means and operating independently to bind the load bearing rails in conjunction with said supporting rails relative to the tie.

In testimony whereof I affix my signature.

GEORGE W. MULLER.
